CLAIM

The ornamental design for an intravenous equipment hanger with mounting support, as shown and described.

DESCRIPTION

FIG. 1 is an upper right front perspective view of an intravenous equipment hanger, including a mounting support, showing our new design, with the hanger bar retracted; FIG. 2 is an upper right rear perspective view thereof with the hanger bar extended; FIG. 3 is a front elevational view thereof with the hanger bar retracted;

FIG. 4 is a right side elevational view thereof with the hanger bar retracted. A left side elevational view would be a mirror image of FIG. 4;

FIG. 5 is a top view thereof with the hanger bar in either the retracted or extended position;

FIG. 6 is a bottom plan view thereof with the hanger bar in either the retracted or extended position;

FIG. 7 is an upper right front perspective view of an intravenous equipment hanger in a second embodiment of our new design, which includes a detachable mounting support and with the hanger bar extended;

FIG. 8 is an upper right perspective view of the hanger unit of the second embodiment, with the hanger bar retracted, shown separated from the mounting support for convenience of illustration;

FIG. 9 is an upper right perspective view of the mounting support of the second embodiment, shown separated from the equipment hanger for convenience of illustration; and, FIGS. 10, 11, 12 and 13 are right side, top, rear and bottom views of the second embodiment, respectively, with the hanger bar extended. A left side elevational view of the second embodiment would be a mirror image of FIG. 10. The broken line showings of environmental hanger hooks of one configuration are for illustrative purposes only and form no part of the claimed design.
